UNITED STATES PATENT OFFICE.

JOHN EMMETT SPRINGER, OF NORFOLK, VIRGINIA.

RAILROAD-TIE AND RAIL-CLAMP.

1,321,256.

Specification of Letters Patent.

Patented Nov. 11, 1919.

Application filed April 11, 1919. Serial No. 289,320.

To all whom it may concern:

Be it known that I, JOHN E. SPRINGER, a citizen of the United States, and a resident of Norfolk, in the county of Norfolk and State 5 of Virginia, have invented a certain new and useful Improvement in Railroad-Ties and Rail-Clamps, of which the following is a specification.

My present invention relates generally to railroad ties, and more particularly to composition ties, my object being the provision of a manufactured tie to replace the usual wooden tie, having novel, effective rail holding means which will not only avoid the use 15 of spikes but will firmly hold the rails against spreading, overturning and creeping and thus avoid the known disadvantages of spike held rails as well as the necessity of employing rail braces and the like particularly at curves.

Other and more specific objects and advantages of my improved tie and rail holding means will appear in the course of the following description, referring to the accompanying drawings from an inspection 25 of which it will be noted that my improved tie presents a neat compact appearance and is strikingly simple and lacking in projections likely to catch in clothes and the like.

30 In the drawing:—

Figure 1 is a side elevation of my improved tie.

Fig. 2 is a transverse sectional view, taken substantially on line 2—2 of Fig. 1, and

35 Fig. 3 is a top plan view.

Referring now to these figures my invention proposes a composition tie generally indicated at 10, which is preferably molded to the desired shape, and which has transverse grooves in its upper surface adjacent to the opposite ends thereof to form rail receiving grooves 11. The lower portions of these grooves are shaped to conform to those portions of a rail to be seated in the grooves, 40 for instance, the base of the usually formed rails or one of the heads of a double headed reversible rail as indicated at 12 in Figs. 1 and 2.

The tie is also provided with transverse 50 hollow recesses 13 along the inner sides of the grooves 11, the walls at the inner sides of which recesses are undercut preferably by beveling the same as seen at 14.

At the opposite or outer sides of the 55 grooves 11, the tie 10 has upwardly and inwardly curved lugs or abutments 15, the

inner portions of which partially overlie the grooves 11 and are shaped to fit into one side of the rails 12 and to snugly engage the webs of the rails from the heads thereof to 60 the bases or rather those portions seated within the grooves 11. These lugs or abutments 15 are preferably integral with the tie 10 and extend across the full width of its upper surface as seen respectively in 65 Figs. 2 and 3.

My invention further proposes clamps 16 of similar or different material with respect to the tie 10 for location within the recesses 13, having flat base portions to seat on the 70 bases of the recesses, terminating at one end in beveled ends 17 to fit the beveled undercut tie walls 14, and having upwardly and outwardly curved portions 18 at their opposite ends to fit into the inner sides of the 75 rails similar to the manner the lugs or abutments 15 engage the outer sides of the rails.

In practice the rails are shifted laterally into the tie grooves and into engagement with the lugs or abutments and the clamps 80 16 are then shifted endwise into the recesses from one side of the tie and after being positioned as shown in the drawing, are secured in place by means of bolts 19 which extend through the lug 15, the rail and the clamp 85 16 at each end of the tie, to securely hold the parts in connected relation.

It is thus obvious that overturning of rails and spreading thereof is effectively prevented, as also rail creeping which latter is defeated by the presence of the bolts 19, and I am thus enabled to provide an effective substitute for wooden ties and at the same time promote more effective rail holding than can possibly be accomplished with the 95 means commonly used in connection with wooden ties.

I claim:—

A composition tie having transverse grooves in its upper surface forming rail 100 seats and provided with upstanding integral lugs at the outer sides of the grooves partially overlying the latter and shaped to snugly engage the web of a rail at one side, between and against its head and base, said 105 tie having transverse recesses at the inner sides of its said grooves of similar depth to the grooves and provided with undercut beveled walls at the inner sides thereof, and clamps having flat bases interfitting in said 110 recesses, and having integral upstanding portions at their outer ends similar to and

opposing said lugs of the tie to engage the inner sides of the rails, said clamps having beveled edges at their inner sides extending beneath the undercut beveled walls of the tie
5 and bolts extending through said tie lugs and the opposing portions of said clamps and adapted to extend also through the rail webs, as described, said lugs and said clamps

having their upper surfaces curved to merge into the upper surface of the tie for the 10 purpose described.

JOHN EMMETT SPRINGER.
